US00D671073S

(12) **United States Design Patent**
Mori et al.

(10) **Patent No.:** US D671,073 S
(45) **Date of Patent:** ** Nov. 20, 2012

(54) **ELECTRIC CONNECTOR**

* cited by examiner

(75) Inventors: **Shigeo Mori**, Kakegawa (JP); **Junya Nakano**, Shimada (JP)

Primary Examiner — Daniel Bui

(73) Assignee: **Yazaki Corporation**, Tokyo (JP)

(74) *Attorney, Agent, or Firm* — Sughrue Mion, PLLC

(**) Term: **14 Years**

(57) **CLAIM**

(21) Appl. No.: **29/406,572**

The ornamental design for an electric connector, as shown and described.

(22) Filed: **Nov. 16, 2011**

DESCRIPTION

(30) **Foreign Application Priority Data**

May 17, 2011 (JP) 2011-011017

(51) **LOC (9) Cl.** 13-03

(52) **U.S. Cl.** D13/133

(58) **Field of Classification Search** D13/107–108,

D13/118–119, 133, 146, 147, 154, 184, 199;
D23/226; 320/104, 107–115; 439/34, 266,
439/310, 352, 372, 500, 660, 680, 700, 862

FIG. 1 is a perspective view of the front, top and right side of an electric connector showing our new design;

FIG. 2 is a perspective view of the rear, top and left side thereof;

FIG. 3 is a front view thereof;

FIG. 4 is a rear view thereof;

FIG. 5 is a right side view thereof, a left side view being a mirror image thereof;

FIG. 6 is a top view thereof;

FIG. 7 is a bottom view thereof; and,

FIG. 8 is a right side view showing a condition in which the handle is turned down thereof.

The broken line portion of the figure drawings is included for the purpose of illustrating environment and forms no part of the claimed design.
